UNITED STATES PATENT OFFICE.

JOHN I. MITROVICH, OF SAN FRANCISCO, CALIFORNIA.

GROOVE CUTTER.

1,411,864.

Specification of Letters Patent. Patented Apr. 4, 1922.

Application filed September 16, 1920. Serial No. 410,717.

To all whom it may concern:

Be it known that I, JOHN I. MITROVICH, citizen of the United States, residing at San Francisco, in the county of San Francisco, 5 State of California, have invented a new and useful Groove Cutter, of which the following is a specification in such full and clear terms as will enable those skilled in the art to construct and use the same.

10 This invention relates to a groove cutter adapted to produce the grooves necessary in cement or artificial stone floors for filling with a compound of a different color to give the appearance of tile floor.

15 It will be understood by those skilled in the art that it is common to produce grooves in artificial stone or cement floors which grooves divide the floor up into a series of blocks. These grooves are then filled with 20 a cementitious material of a different color from the body of the floor so the finished floor presents the appearance of a series of separate tiles whereas the blocks are really divided by shallow grooves only.

25 It will also be understood that the grooves are cut in the stone at a time when it has set sufficiently to be hard, but not hard enough to seriously interfere with the grooving operation.

30 Another object of the invention is to produce a grooving machine capable of working on either side of the motor used, thereby enabling the cutter to make a groove very close to the walls of the corridor or 35 room.

Another object of the invention is to produce a straight edge track that can be connected together in sections to enable the apparatus to produce grooves in a floor of 40 any extent. These sections are connected together by any suitable means and in such lengths as the extent of the floor requires. It will be understood by those skilled in the art that the track sections may be made 45 straight if the grooves are to be cut straight, in which event the apparatus follows the straight track or if the grooves are to be cut on a curve the curved track is used and the cutter follows the curved track.

50 Other objects of the invention will appear as the description proceeds.

An embodiment of the invention is shown in the accompanying drawings in which the same reference numeral is applied to the 55 same portion throughout, but I am aware that there may be modifications thereof.

Figure 1 is a plan view of the complete machine.

Fig. 2 is a side elevation of the complete machine.

Fig. 3 is a view of the complete machine looking from the left Fig. 2 and

Fig. 4 is a plan view of the floor as it appears when the grooves are finished.

The numerals 1 to 3 inclusive indicate 65 bases duplicates of and interchangeable with one another. Each of these bases has a register pin 4 which projects into the next adjacent base and plates 5 and 6 are used to connect one base with another, bolts 7 and 80 8 and ring nuts 9 and 10 being used for securing two of the bases together. The bases are each provided with tracks 10' and 11 which are aligned with the tracks of the next adjacent base when the bases are connected.

Mounted on the tracks 10', 11 is a truck 85 consisting of a flat base 12 supported by four grooved wheels 13 to 16 inclusive, which wheels roll on the tracks 10', 11. A motor 17 is rigidly mounted on the base 12, said motor frame having a projecting hollow bearing 18 for the shaft 19 and for the swinging arm 20. At the other end the motor frame is provided with a fixed projecting lug 21 to carry the swinging arm 22. The two arms are connected to their supports by means of bearing clamps 23, 24 detachable therefrom.

The two arms 20, 22 are connected at their 90 ends opposite the motor by means of the bar 25 and two clamps 26, 27 and they are connected at a middle portion by a rod 28 which passes through holes in the arms 20, 22 and which is held in a given position by the set 95 screws 29, 30.

The rod 28 carries two brackets 31 which brackets are each held in the position shown in Fig. 2 by a bolt 33. The brackets 31 each have an adjustable rod 34 at the lower end 100 of which in each case is a grooved roller 35. The two rollers 35 rest on the tracks 10', 11 and the adjustment of the rods 34 determines the depth of the groove cut in the floor.

The rod 25 is held by the clamps 26 and 105 27 sufficiently tight to prevent its rotation but not tight enough to prevent the same from being turned by the handle 36 when the cutter is turned so the arms project to 110 the right of the motor Fig. 2.

The cutter 37 is journaled on the end of

the rod 25, collars 38 and 39 holding the cutter in the proper position at all times. The saw arbor is provided with a sprocket wheel 40 around which a sprocket chain 41 passes, said chain also passing around a sprocket wheel 42 on the motor shaft 19.

In operation the bases carrying the tracks are laid on the floor and are connected up in such lengths as may be necessary to cut 10 the grooves in the floors from one wall to the other.

The motor base is then mounted on the tracks and a workman cuts the grooves by pushing the motor along the tracks with 15 the handle 36. When a wall is approached the position of the saw may be reversed and the groove may then be cut as close to the wall as the saw itself will allow.

What I claim is as follows, but various 20 modifications may be made in the construction shown in the drawings and above particularly described form, within the purview of my invention:

1. A floor grooving machine comprising 25 a motor, a wheeled truck for the motor, a pair of swinging arms movable concentrically with the motor shaft, a bar connecting said arms, a saw carried by the arms, means to rotate the saw from the motor shaft, a 30 pair of adjustable brackets carried by the bar connecting the arms and wheels connected with said brackets to gauge the depth of cut made.

2. A floor grooving machine comprising a 35 motor, a wheeled truck therefor, a pair of swinging arms movable concentrically with the motor shaft, a bar connecting said arms, a shaft journaled in the ends of said arms, a saw carried by the shaft, means to rotate the saw from the motor shaft and adjustable wheels carried by the bar to determine 40 the depth of cut.

3. A floor grooving machine comprising a motor, a wheeled truck for the motor, arms 45 movable concentrically with the motor shaft, a saw carried by the arms, means to drive the saw from the motor shaft, and a pair of wheels adjustably connected to the arms to determine the depth of cut made by the saw, the arms and gauge wheels being reversible to permit the saw to be used on both sides of the motor.

4. A floor grooving machine comprising a series of bases, means to detachably connect the bases, tracks carried by the several 55 bases to be aligned when the bases are connected, a motor, a wheeled truck for the motor movable on the tracks of the bases, arms carried by the motor, a bar connecting said arms, a saw carried by the arms, means to 60 drive the saw from the motor shaft brackets adjustable longitudinally and radially of the bar connecting the arms and wheels carried by said brackets to gauge the depth of cut produced by the saw.

5. A machine of the class described comprising a motor, a wheeled truck therefor, a pair of swinging arms movable concentrically about the motor shaft to be used on both sides of the motor, a rotary tool 70 carried by the arms and means to rotate the tool from the motor shaft.

6. A machine of the class described comprising a motor, a pair of swinging arms movable concentrically about the motor 75 shaft to be used on both sides of the motor, a bar rigidly connecting said arms, a shaft revolvably journaled in the ends of said arms, a rotary tool carried by the shaft and means to rotate the tool from the motor shaft.

In testimony whereof I have hereunto set my hand this 7th day of September, A. D. 1920.

JOHN I. MITROVICH.
